WILLIAM F. DRAPER, OF HOPE DALE, MASSACHUSETTS.

Letters Patent No. 106,140, dated August 9, 1870.

IMPROVEMENT IN SPINNING-RING.

The Schedule referred to in these Letters Patent and making part of the same.

To all persons to whom these presents may come:

Be it known that I, WILLIAM F. DRAPER, of Hopedale, of the county of Worcester, of the State of Massachusetts, have made a new and useful invention having reference to the Rings and their Supporters of Ring and Traveler Spinning-Frames; and I do hereby declare the same to be fully described in the following specification, and represented in the accompanying drawing, of which—

Figure 1 is a top view, and

Figure 2 a transverse section of a ring, ring-rail, and ring-supporter, exhibiting the latter as constructed in accordance with my invention.

Figure 3 is a top view, and

Figure 4 a side elevation of the ring-supporter.

Figure 5 is a transverse section of a ring with one race;

Figure 6 being a transverse section of a ring formed with two races, either of such rings being adapted for use with my improved supporter.

Preparatory to describing my invention or improvement, I would remark that I am aware that at the time of the conception of it by me, a ring-supporter, consisting of an annulus split or cut entirely through at one part of its circumference rebated to receive the ring, and formed to enter the socket of the ring-rail, and with a shoulder to rest on such rail, and to be held in place in the rail and sprung upon the ring by a screw screwed into the rail, was not new, and therefore I make no claim thereto as my invention.

In carrying out my invention or improvement, I employ a rebated annulus to support the ring, whether such ring has two races or one, and instead of making cylindrical the part which enters the ring-rail, I make it tapering or conical, and I make down in the supporter from its top, a distance of about two-thirds of its altitude, one or more saw-kerfs or vertical cuts,

the same being to allow and cause the ring-supporter to contract upon the ring, while such supporter may be forced down into its socket in the ring-rail.

By this construction of the supporter, the cuts being arranged radially thereof, the screw in the rail, if used, simply performs the function of holding the supporter in the rail, and preventing its displacement by any of the ordinary operations of spinning.

Where the screw is used for contracting a slotted holder, and thereby confining the ring thereto, it tends to decentralize the ring with respect to the spindle, while, with my improvement, the socket in the rail being drilled so as to be concentric with the spindle, the ring will remain so, since the ring will be held firmly by the pressure upon all the sides of the holder by the outside of the socket in the rail, so that the holder and ring, if well constructed, will be concentric with the said socket and the spindle.

In the drawing—

A denotes the ring-rail, B, the ring, and C, the ring-carrier or supporter, *a* being the tapering or conical shank or part to enter the circular socket *b* of the rail B.

The radial cuts or saw-kerfs made in the ring-carrier or supporter, are represented at *c c c* as carried down from the top of the supporter through its shoulder *d*, and down into the conical shanks nearly to its bottom.

I claim—

The rebated ring-supporter C, provided with the conical shank, and with one or more cuts or kerfs, *c c c*, arranged in such supporter, substantially as hereinbefore described.

WM. F. DRAPER.
